(57) CLAIM

I claim the ornamental design for a dress form, as shown and described.

DESCRIPTION

FIG. 1 is a perspective view of a dress form, showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front perspective view showing the dress form partially open; and,

FIG. 8 is an enlarged view of the adjuster of the dress form. The broken lines are shown for illustrative purposes only and form no part of the claimed design. The indicia has been omitted from the adjusters in FIGS. 1-7 and 7 for convenience of illustration.
